CLAIM

The ornamental design for a golf tee, as shown and described.

DESCRIPTION

FIG. 1 is a perspective view of a golf tee in accordance with my new design;
FIG. 2 is a left side view of golf tee as shown in FIG. 1;
FIG. 3 is a right side view of golf tee as shown in FIG. 1;
FIG. 4 is a top view of golf tee as shown in FIG. 1;
FIG. 5 is a bottom view of golf tee as shown in FIG. 1;
FIG. 6 is a front view of golf tee as shown in FIG. 1; and,
FIG. 7 is a back view of golf tee as shown in FIG. 1.
The broken lines in the figures depict environmental subject matter that forms no part of the claimed design.

1 Claim, 2 Drawing Sheets
